UNITED STATES PATENT OFFICE.

IVOR D. THOMAS, OF PALMYRA, AND PAUL H. DOUGLAS, OF CLEVELAND HEIGHTS, OHIO, ASSIGNORS TO THE WELLMAN-SEAVIER-MORGAN COMPANY, OF CLEVELAND, OHIO, A CORPORATION OF OHIO.

PUSHER-RAM STOP AND SUPPORT.

Application filed February 26, 1926. Serial No. 90,940.

This invention relates to pusher rams such as are employed for discharging coke from coke ovens and has for its object to provide a mounting for the ram by which the rear end of the ram is prevented from drifting beyond its support on the ram carriage and dropping down out of alignment with its support.

The ram of a coke pusher is supported on rollers and is projected into and retracted from an oven by means of a motor driving a pinion which meshes with a rack on the ram.

In order to prevent over-travel of the ram interengaging stops are provided on the ram and its supporting frame to limit the movement of the ram. The maximum torque which the operating motor must develop is so great that it is impracticable to design these stops so that they will withstand repeated blows of the ram with the full power on the motor. Therefore, limit switches have been provided to cut off the motor current and set the motor brake before the stops on the ram strike the stops on the supporting frame so that the force of the impact of the ram stops against the frame stops is greatly reduced.

Occasionally, however, the limit switches fail to function properly and the ram may drift through the stops so that its rear end runs off the driving pinions and drops down onto the main frame of the machine some distance below.

It requires a pull of several tons to raise the end of this ram, and since outside means for doing this work must be provided, considerable time elapses, even under the most favorable conditions, before the ram can be put back in place ready for operation. During this time the major portion of the ram is in the oven subjected to a high temperature, and any delays, under such circumstances, not only hold up the operation of the coke plant, but also seriously affect the life of the ram.

The present invention provides means for preventing the rear end of the ram from dropping out of alignment with its runway in the event that the main stops are broken, and also provides secondary stops for retaining the rear end of the ram upon the auxiliary support.

The following description and accompanying drawings set forth in detail certain

means embodying the invention, the disclosed means, however, constituting but one of the various mechanical forms in which the principle of the invention may be employed.

Reference should be had to the accompanying drawings forming a part of this specification in which Fig. 1 is a side elevation of the pusher ram and the ram supporting members; Fig. 2 is a stop plan view of the pusher ram and the ram guideway; Fig. 3 is an end elevation of the ram and the ram supporting members looking toward the rear end of the ram; Fig. 4 is a fragmentary side elevation showing the rear end of the ram in the position in which it is held by the secondary stops after it has drifted past the main stops and off the driving pinion.

Referring to the accompanying drawings, the supporting structure indicated by the numeral 1 is mounted upon a suitable carriage adapted to travel along the front of a battery of coke ovens, but since the present invention concerns only the mounting of the pusher ram, a portion only of the supporting structure 1 is shown. A ram 2 is provided with a pusher head 3 of a size but slightly less than that of the interior of the oven chamber so that it is adapted to enter the chamber and discharge the coke therefrom as the ram is operated to push the head 3 through the chamber. The ram 2 is also provided with a runner 4 attached to the under side thereof rearwardly of the head 3, the runner 4 being adapted to slide along the floor of the coke oven as the ram is pushed therethrough and forming an auxiliary support for the ram. The ram 2 is supported in a guideway which is formed by front, rear and intermediate standards 5, 6 and 7, each of which has spaced posts between which the ram 2 is mounted. The standards 6 and 7 are provided with flange supporting rollers 8 upon which the ram 2 travels, and the standard 5 is provided with a combined supporting roller and pinion 9 which meshes with a rack 10 which extends along the under side of the ram 2. The standards 5 and 7 are also provided with flanged guide rollers 11 which engage with the top of the ram 2, the supporting and guide rollers forming a guideway in which the ram travels.

100
105

The ram 2 is reciprocated by means of a suitable electric motor (not shown) which drives the pinion 9, and limit switches 12 and 13 are operated by trip members 14 and 15 projecting from the side of the ram. When the ram approaches its forward limit of movement the trip member 14 engages with the limit switch 12 to cut off the current to the driving motor, and when the ram 10 approaches its rearward limit of movement the trip member 15 engages with the limit switch 13 to cut off the current to the motor.

In order to prevent the ram from drifting past the forward supporting roller and driving pinion 9, the supporting standard 5 is provided on opposite sides of the ram with inwardly projecting stop lugs 16 which are engaged by stop lugs 17 attached to the ram adjacent the rear end thereof when the rear end of the ram comes to a position directly over the pinion 9. Brackets 18 are attached to the standard 5 upon opposite sides of the ram 2 and project forwardly from the standard 5. Horizontally disposed bars 19 are attached to the inner faces of the brackets 18 and, at the forward ends of the brackets 18, are attached secondary stop lugs 20. At the rear end of the ram there are attached stop lugs 21 positioned to engage with the secondary stops 20 in the event of failure of the main stops 16 and 17. The bars 19 form supporting ledges upon which the stop lugs 21 of the ram are adapted to slide when the rear end of the ram has drifted beyond the driving pinion 9, the bars 19 forming auxiliary supports for the rear end of the ram after the ram has drifted past the main stop 16.

In the normal operation of the ram, the driving motor is stopped and the motor brake applied by the operator reversing the controller or by actuation of the limit switches prior to the engagement of the main stops 16 and 17 so that the main stops are ordinarily not subjected to excessive strain. If the limit switches should fail to function properly, the stop lugs 17 might be driven with great force against the stop lugs 16 causing the lugs to break and the rear end of the ram to drift past the driving pinion 9. In this event the rear end of the ram is supported by the stop lugs 21 sliding along the supporting bars 19 and the ram will be brought to a stop by engagement of the secondary stops 20 and 21. In order to withdraw the ram from the oven it is only necessary to pull the ram back until the rack 10 is reengaged with the pinion 9 and to operate the motor to retract the ram.

Having described our invention what we claim is:—

1. In a device of the character described, a pusher ram, a support having a guideway in which the ram is slidably supported,

means for moving the ram back and forth in the guideway, stop members on the ram and support for preventing the rear end of the ram from drifting past the forward end of the guideway, and auxiliary means operable upon failure of said stop members for stopping the ram and supporting the same with its rear end beyond but at substantially the same level as the guideway.

2. In a device of the character described, a pusher ram, a support having a guideway in which the ram is slidably supported, means for moving the ram back and forth in the guideway, main and secondary stop members secured to the ram adjacent the rear end thereof, a main stop member carried by the support adjacent the end of the guideway in the path of movement of the main stop member on the ram, and secondary stop members carried by the support in the path of movement of the secondary stop member of the ram, said secondary stop members being engageable to stop the ram in the event of failure of the main stop members.

3. In a device of the character described, a pusher ram, a support having a guideway in which the ram is slidably supported, means for moving the ram back and forth in the guideway, stop members on the ram and support for preventing the rear end of the ram from drifting past the forward end of the guideway, secondary stop members projecting from opposite sides of the ram at the rear end thereof, brackets carried by the support and extending on opposite sides of the ram in advance of the guideway, supporting ledges carried by the brackets upon which the secondary stops of the ram are adapted to slide, and stop members carried by the brackets with which the secondary stop members of the ram are adapted to engage in the event of failure of the first mentioned stops.

4. In a device of the character described, a pusher ram having a rack on the underside thereof, a support having a guideway in which the ram is slidably supported, a pinion meshing with said rack, co-operating stop members carried by the support at the forward end of the guideway and the ram adjacent the rear end thereof to stop said ram before the rack passes off of said pinion, auxiliary supporting members carried by the support forwardly of said pinion and by the ram adjacent the rear end thereof for slidably supporting the ram with the rack forwardly of the pinion, and secondary stops on the support and ram for preventing the rear end of the ram from drifting off of the auxiliary supporting members.

In testimony whereof, we hereunto affix our signatures.

IVOR D. THOMAS.
